US0D1034720S

(12) **United States Design Patent** (10) **Patent No.:** **US D1,034,720 S**
(45) **Date of Patent:** **** Jul. 9, 2024**

(54) **3D PRINTER**

- (71) Applicant: **Shenzhen Elegoo Technology Co., Ltd.**, Shenzhen (CN)
- (72) Inventors: **Zhonghua Li**, Shenzhen (CN); **Guihua He**, Shenzhen (CN)
- (73) Assignee: **Shenzhen Elegoo Technology Co., Ltd.**, Shenzhen (CN)
- (**) Term: **15 Years**
- (21) Appl. No.: **29/932,732**
- (22) Filed: **Mar. 15, 2024**
- (51) LOC (14) Cl. **15-09**
- (52) U.S. Cl. **USPC D15/122**

(57) **CLAIM**

The ornamental design for a 3D printer, as shown and described.

DESCRIPTION

FIG. 1 is a front, right and top perspective view of a 3D printer, showing our design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is an enlarged view of detail 9 in FIG. 1.

FIG. 10 is an enlarged view of detail 10 in FIG. 1.

FIG. 11 is an enlarged view of detail 11 in FIG. 1.

FIG. 12 is an enlarged view of detail 12 in FIG. 1.

FIG. 13 is an enlarged view of detail 13 in FIG. 1.

FIG. 14 is an enlarged view of detail 14 in FIG. 2.

FIG. 15 is an enlarged view of detail 15 in FIG. 2; and,

FIG. 16 is an enlarged view of detail 16 in FIG. 2.

The dashed broken lines depict portions of the 3D printer that form no part of the claimed design. The dot-dash broken lines in FIGS. 1-2 and 9-16 depict the boundaries of the enlargements that form no part of the claimed design.

1 Claim, 16 Drawing Sheets
